UNITED STATES PATENT OFFICE.

ANNABELL C. BULL, OF PEORIA, ILLINOIS.

DESIGN FOR A KNEE-PROTECTOR.

SPECIFICATION forming part of Design No. 22,767, dated September 5, 1893.

Application filed June 5, 1893. Serial No. 476,698. Term of patent 3½ years.

To all whom it may concern:

Be it known that I, ANNABELL C. BULL, a citizen of the United States, residing at Peoria, in the county of Peoria and State of Illinois, have invented a certain new Design for Knee-Protectors; and I do hereby declare that the following is a full, clear, and exact description of the invention, which will enable others skilled in the art to which it appertains to make and use the same.

My invention relates to a certain new and original design for knee protectors, by means of which a neat design is provided, reference being had to the accompanying drawing showing the same.

The figure is a plain face view showing my design which is deemed sufficient to fully illustrate it.

The leading feature of my design consists

in the general rectangular form with the respective sides of the figure or protector bearing to and from the perpendicular with the respective outer corners somewhat extended from the lower body and provided with a general irregular edge, and a divided extension over the top, and it is supplied with an ornamental slip and clasp attached to its lower corner as shown.

What I claim is—

The design for a knee protector as herein shown.

In testimony whereof I affix my signature in presence of two witnesses.

ANNABELL C. BULL.

Witnesses:

W. V. TEFFT,
MINNIE HALEY.
